US00D838570S

(12) **United States Design Patent** (10) Patent No.: **US D838,570 S**
(45) Date of Patent: **** Jan. 22, 2019**

(54) **ACCESSORY REMOVER FOR MOBILE
TELEPHONE**

(71) Applicant: **AAUXX KOREA CO., LTD.**, Seoul
(KR)

(72) Inventor: **Jintae Jang**, Seoul (KR)

(73) Assignee: **AAUXX KOREA CO., LTD.**, Seoul
(KR)

(**) Term: **15 Years**

(21) Appl. No.: **35/504,354**

(22) Filed: **Jul. 24, 2017**

(80) **Hague Agreement Data**

Int. Filing Date: **Jul. 24, 2017**

Int. Reg. No.: **DM/098292**

Int. Reg. Date: **Jul. 24, 2017**

Int. Reg. Pub. Date: **Jan. 26, 2018**

(51) **LOC (11) Cl. 08-05**

(52) **U.S. Cl.**

USPC **D8/89**

(58) **Field of Classification Search**

USPC D14/217; D8/40, 47, 48, 88, 89

CPC B66F 15/00; B25C 11/00
